UNITED STATES PATENT OFFICE.

GEORGE W. WHITEMAN, OF PHILADELPHIA, PENNSYLVANIA, ASSIGNOR TO THE
RAIL JOINT COMPANY, OF NEW YORK, N. Y., A CORPORATION OF NEW YORK.

TIE-PLATE MOUNTING FOR U-RAIL SECTIONS.

1,388,135.

Specification of Letters Patent. Patented Aug. 16, 1921.

Application filed May 24, 1919. Serial No. 299,390.

To all whom it may concern:

Be it known that I, GEORGE W. WHITEMAN, a citizen of the United States, residing at Philadelphia, in the county of Philadelphia and State of Pennsylvania, have invented certain new and useful Improvements in Tie-Plate Mountings for U-Rail Sections, of which the following is a specification.

10 This invention relates to a tie plate structure affording an effective support and brace for a U-rail section.

A necessary modern complement of the track appurtenances for a U-rail is a well 15 designed tie plate that will provide for the correct seating of the rail section on the ties between the joint ties, and in such a manner that any tendencies of the foot portions of the U-section to spread or buckle 20 inwardly or outwardly shall be effectively resisted. It is, therefore, the principal object of the present invention to provide a tie plate for U-rail section which affords 25 a wide and substantial seat for the rail, while at the same time so bracing the foot portions of the rail as to positively prevent inward or outward movement or displacement when the wheel loads are imposed 30 thereon.

35 A further object of the present invention is to incorporate with the tie plate structure a novel design of U-rail section which not only readily adapts itself to the tie plate functions referred to, but also provides spiking channels which permit the use of the screw spikes, or equivalent fastenings, to the best advantage.

With these and other objects in view 40 which will be readily understood by reference to the drawings and description herein, the invention consists in the novel tie plate construction, in combination with the U-rail section, hereinafter more particularly pointed out and claimed.

45 Though susceptible of some structural modification without departure from the invention, a preferable embodiment is shown in the accompanying drawings, in which:—

Figure 1 is a perspective view of the improved tie plate mounting for U-rail sections, constructed in accordance with the present invention.

Fig. 2 is a sectional elevation of the improved mounting.

Fig. 3 is a top plan view of the novel tie plate.

Like references designate corresponding parts in the several figures of the drawings.

The present invention contemplates a tie plate mounting designed with special reference to a novel U-rail section intended to be rolled from a single billet or bloom according to the plan of metal distribution specified in another application filed by me this day.

The said U-rail section includes a solid head member 1, the opposite inclining side webs or legs 2-2 and a horizontal base flange 3 extending outwardly from the lower edge of each web or leg. In connection with this U-rail section a distinctive feature thereof resides in a formation which produces at the upper side of each flange a horizontal longitudinally extending fishing channel 4. And, in carrying out the present invention the horizontal fishing channel 4 at the upper side of each base flange is utilized to receive the heads 5 of the screw spikes 6, or equivalent fastenings, which are adapted to extend through the spike holes 7 and 8 which are formed respectively in the base flanges 3 of the U-rail section and in the tie plate body 9.

The tie plate body 9 which is adapted for use with the U-rail section described may be 85 readily formed in the passes of a rolling mill since the same is of a simple and economical design. However, the tie plate may be made by drop forging or other method, but regardless of the way in which 90 it is made the characteristic structural feature of the tie plate is the provision thereof at its upper side with the separate rail seating channels 10 formed between a pair of inner and outer abutment ribs 11 and 12. 95 Each seating channel is formed with a flat rail seat 13 substantially coextensive in area with the flat underface of the base flange 3 so that such flange may have a correct seating engagement with the top surface of the 100 tie plate and the distance between the upstanding abutment ribs 11 and 12 is substantially equal to the width of the base flange 3 seated therebetween so that the rail flange will have a braced engagement with 105 the said ribs 11 and 12 which will positively prevent lateral movement of the rail, or buckling in or out of the base flange and

web thereof, when the wheel loads are passing over the rail.

The ribs 11 and 12 are formed at one side with the shoulder faces 14 corresponding in 5 inclination to the opposing faces of the rail which are adapted to find an abutment thereagainst, thus providing a nice fit between the channeled base flanges of the rail and the parts of the tie plate body with 10 which they engage so that when the base flanges of the rail are drawn tightly into engagement with the tie plate by the screwing up of the spikes 6 a substantial, durable and effective tie plate mounting will be the result. 15

The tie plate itself may be fastened to the tie by the screw spikes 15 or equivalent fastenings.

From the foregoing it is thought that the 20 construction, function and advantages of the herein described tie plate mounting will be apparent without further description and it will be understood that changes in the 25 form, proportion and minor details of construction may be resorted to without depart-

ing from the spirit or sacrificing any of the advantages of the invention.

I claim:—

1. A tie plate mounting for U-rail sections comprising, in combination, the tie plate 30 having at the top two pairs of spaced parallel abutment ribs forming seats between them, a U-rail section having base flanges each of which is seated between a pair of the said ribs, and fasteners engaging the base 35 flanges of the rail and said tie plate.

2. A tie plate mounting for U-rail sections comprising, in combination, the tie plate having at the top a pair of spaced rail seating channels, a U-rail section having 40 channeled base flanges interlocked within the rail seating channels, and fasteners having their heads seated within the channels of the U-rail section.

In testimony whereof I hereunto affix my 45 signature in the presence of two witnesses.

GEORGE W. WHITEMAN.
